UNITED STATES PATENT OFFICE

135,201

DESIGN FOR AN ILLUMINABLE MAKE-UP CABINET

Martin J. Grady, Decatur, Ill.

Application July 22, 1941, Serial No. 102,372

Term of patent 3½ years

To all whom it may concern:

Be it known that I, Martin J. Grady, a citizen of the United States and a resident of the city of Decatur, county of Macon, and State of Illinois, have invented a new, original, and ornamental Design for an Illuminable Make-Up Cabinet, of which the following is the specification, and reference being had to the accompanying drawing, forming a part thereof.

Fig. 1 is a front perspective view of an illuminable make-up cabinet embodying my new design, with the doors in open and the service shelf in lowered positions;

Fig. 2 is a top plan view of Fig. 1;

Fig. 3 is a front elevational view thereof in closed position; and

Fig. 4 is a side elevational view of Fig. 3.

I claim:

The ornamental design for an illuminable make-up cabinet, as shown.

MARTIN J. GRADY.
